US0D1041026S

(12) **United States Design Patent** (10) Patent No.: **US D1,041,026 S**
(45) Date of Patent: ** Sep. 3, 2024

(54) **SPECIMEN TEST TUBE WITH LID FOR LABORATORY AND MEDICAL USE**

(71) Applicant: **MAPLE LS CORPORATION**,
Hongcheon-gun (KR)

(72) Inventor: **Yun Park**, Seoul (KR)

(73) Assignee: **MAPLE LS CORPORATION**,
Gangwon-Do (KR)

(**) Term: **15 Years**

(21) Appl. No.: **35/518,530**

(22) Filed: **Apr. 6, 2023**

(80) **Hague Agreement Data**

Int. Filing Date: **Apr. 6, 2023**

Int. Reg. No.: **DM/229530**

Int. Reg. Date: **Apr. 6, 2023**

Int. Reg. Pub. Date: **Oct. 6, 2023**

(30) **Foreign Application Priority Data**

Apr. 5, 2023 (KR) 30-2023-0012886

(51) **LOC (14) Cl.** **24-02**

(52) **U.S. Cl.**

USPC **D24/224**

(57) **CLAIM**

The ornamental design for a specimen test tube with lid for laboratory and medical use, as shown and described.

DESCRIPTION

1. Specimen test tube with lid for laboratory and medical use

1.1 : Perspective

1.2 : Front

1.3 : Back

1.4 : Left

1.5 : Right

1.6 : Top

1.7 : Bottom

The portions of the specimen test tube with lid for laboratory and medical use shown in broken lines form no part of the claimed design.

1 Claim, 7 Drawing Sheets
